DISCHARGE GATE APPARATUS

William G. Davenport, Jenkintown, Pa., Robert K. Hampton, Garden City, N.Y., and Alan M. Katzen, Philadelphia, Pa., assignors to Beaumont Birch Company, Philadelphia, Pa., a corporation of Pennsylvania
Filed May 26, 1960, Ser. No. 31,851
12 Claims. (Cl. 222—108)

This invention relates generally to drained gates for controlling the delivery of bunkered material to any suitable receiving apparatus. Commonly gates of the type to be described are installed below bunkers which hold material containing a substantial amount of water, as for example, coal bunkers wherein the stored coal also contains coal wash water, and hot ash storing bunkers wherein the ash contained therein has been quenched and, therefore, also contains a substantial amount of water. For purposes of illustration, the present invention hereinafter described is illustrated in the drawings as embodied in an ash gate.

In order to adequately quench the hot ash deposited in the bunker, immediately below which the gate according to the invention is located, substantial amounts of water are employed and the gate drainage apparatus must be capable of carrying off this water without spillover or overflow onto the floor underlying the gate. In some applications, the volume of quench water required to be drained may readily exceed fifty gallons per minute and presently known drained gate structures are generally unable to handle such a water volume. Moreover, when the stand of bunkered material is of any substantial height, a considerable head of water may exist in the bunker. Since the bunker closing gate is generally spaced fairly closely below the bottom of the bunker discharge chute, as for example approximately one-eighth of an inch below, it will be appreciated that bunkered water under any appreciable head will be discharged laterally outward through the small clearance between the chute bottom and the top of the gate at a relatively high velocity. With gates of the usual type having upward and outwardly sloped side walls, the drain water flowing laterally outward across the top of the gate bottom at high velocity can flow right up the side walls and over the sides of the gate and thereby fall to the floor below. Since this condition arises as a consequence of the velocity of the flowing drain water, it may occur even in those cases where the gate would otherwise normally be able to handle the volume of drain water.

Thus, the instant invention contemplates the solution of two problems, namely the provision of a drained gate with means for draining large volumes of water from the bunkered material above the gate, and also the provision of means for preventing high velocity drain water from escaping the drainage system. While it may at first be considered that the two problems solved by the present invention are essentially independent ones, this is not in actuality the case and the means for overcoming the volume drainage requirements problem also contributes to the solution of the velocity problem. Accordingly, it is a primary object of this invention to provide a novel drained gate apparatus wherein means are provided for substantially increasing the ability of the gate to handle large quantities of drain water and to simultaneously prevent the escape of the drain water from the drainage system.

Another object of this invention is to provide novel drained gate apparatus which includes means for confining high velocity drain water to the drainage system and preventing spillover or spraying thereof out of the drainage system.

Yet another object of this invention is to provide novel drained gate apparatus of substantially increased capacity

2

for handling drain water by structural changes to the gate which do not necessitate changes to other parts of the apparatus.

Still another object of the present invention is to provide novel drained gate apparatus capable of handling very large quantities of drain water by employing a construction which utilizes the principle of gravitic flow.

The foregoing and other objects of the invention will become apparent from a reading of the following specification in conjunction with an examination of the appended drawings, wherein:

FIGURE 1 is a side elevational view of the drained gate according to the invention installed upon an ash bunker to close the discharge chute thereof;

FIGURE 2 is a top plan view of the drained gate according to the invention as would be seen when viewed from above with the overlying bunker removed, but with the bunker chute remaining;

FIGURE 3 is a transverse sectional view through the drained gate according to the invention as would be seen when viewed along the lines 3—3 of FIGURE 2;

FIGURE 4 is a longitudinal sectional view through the drained gate according to the invention as would be seen when viewed along the lines 4—4 of FIGURE 2;

FIGURE 5 is an enlarged fragmentary view, in section, of that portion of the apparatus within the phantom circle on FIGURE 3.

In the several figures, like elements are denoted by like reference characters.

Turning now to the drawings and considering first the views of FIGURES 1 and 2, there will be seen a storage bunker 10 whose inside walls are lined with a refractory material 11, such as fire brick, and which has affixed to the bottom opening thereof a bunker chute 12 extending vertically downward therefrom and having an open bottom adapted to be opened or closed by the shiftable gate 22. The bunker chute 12 is provided with the vertically extending front wall 13, rear wall 14 and pair of opposite side walls 15. Formed integrally with the chute 12 at the top thereof is a peripherally extending top mounting flange 16 apertured with the bolting holes 17 and by means of which the chute 12 may be bolted to the bottom of the bunker 10. As best seen in the view of FIGURE 4, the outer surfaces of the front and rear chute walls are provided with substantially horizontally extending reinforcing flanges designated as 18 on the rear wall 14 and designated as 19 on the front wall 13.

As best seen in FIGURES 3 and 4, integrally formed with or subsequently secured to the chute side walls 15 on the outer surfaces thereof and extending at an inclination to the horizontal are a pair of side wall mounted inclined tracks 20. The tracks 20, along which the gate 22 is shiftable in a manner to be subsequently described, extend from a point to the right of the chute rear wall 14 over toward the left on a downward inclination along the chute side walls 15 to a point just short of the chute front wall 13, then turning upward through the short up-turned section 21 and terminating at the front wall reinforcing flange 19. The short up-turned track section 21 proximate the chute front wall 13 acts as a stop to the forward motion of the gate 22 by preventing the gate carrying rollers 33 from further rotation in the direction of the chute front wall.

As best seen in the showings of FIGURES 3 and 5, the bunker chute closing gate 22 is generally of U-shape in cross section, the bottom region of the U being of somewhat modified construction. The lower region of the gate 22 is seen to be formed of a horizontally extending bottom portion 23 having a pair of up-turned side edges 24 which together form a trough lined with a refractory material 25. Extending laterally outward from each of the up-turned edges 24 is an outwardly turned generally

horizontally extending portion 26 which each themselves turn vertically upward generally parallel to the chute side walls 15 and terminate in horizontally extending flange portions 28 extending in opposite direction from the up-turned portions 27, so that each flange 28 extends inward toward the chute side walls and outward therefrom. The inward projecting portions of the flanges 28 are observed to closely non-engagingly underlie the tracks 20 mounted on the outside of the chute side walls 15, and also to form with the below-lying gate vertical portions 27 and horizontal portions 26 a pair of side drainage channels 29. This same drainage channel structure is also formed at the back end of the gate 22, as best seen in the showing of FIGURE 4, so that the drain channel 29 is continuous around the sides and rear of the gate 22. The front end of the gate 22, which is observed in FIGURES 1 and 4 as projecting into the drain box 38, is not provided with the drain channel forming vertical portions 27 or horizontal flange 28, but is instead provided with a drip ledge 30 so that the water draining from the bunker may flow through the drain channels 29 and along the top surface of the gate 22 toward the drain box 38 and be discharged thereinto over the drip ledge 30.

Extending vertically upward from the side flanges 28 are the gate 22 side walls 31, to the inner sides of which are rotatably journaled the rollers 33 seated upon and riding along the tracks 20 secured to the chute side walls 15. Formed along the upper edge of each of the side walls 31 are a plurality of teeth which form solid toothed racks 32. Disposed above the racks 32 and in meshed engagement therewith are the teeth of a pair of pinions 36 fixedly mounted upon a rotatable shaft 34 journaled in bearings 35 carried by the upper portions of the track structures 20 located to the right of the chute rear wall 14. The pinion shaft 34, as best seen in FIGURE 2, extends for a distance beyond the chute side walls on one side and has affixed thereto a chain wheel 37 by means of which the shaft 34 and pinions 36 may be rotated to cause the teeth of the pinions 36, which are intermeshed with the solid toothed racks 32, to drive the entire gate 22 to the right in order to open the chute bottom or to the left to close the chute bottom, the entire gate 22 being shifted along the tracks 20 by means of the rollers 33 journaled in the gate side walls 31.

Depending from and secured to the bunker chute front wall reinforcing flange 19 by means of the bolts 40 is the enclosed drain box 38 having an outlet 39 at one end thereof and being provided with a side opening 41 into which the drip ledge 30 of the gate 22 projects when the gate is closed. The drain box 38 is inclined, as best seen in the showing of FIGURE 3, so that the collected water tends to flow by gravity out through the outlet 39, which in general will be coupled to a run-off system, such as a run-off gutter. The lower edge of the drain box side opening 41 which is normally disposed immediately below the gate drip ledge 30 is provided with an inwardly somewhat down-turned flange 42 to prevent relatively high velocity drain water running off of the gate drip ledge from flowing around the curved bottom of the drain box 38 and upwardly out through the side opening 41. Similarly, a second flange 42 is formed on the inside of the drain box 38 extending substantially horizontally and parallel to the side opening flange but being disposed along the drain box wall remote from the gate 22. Understanding now the basic structure of the apparatus, the following discussion of the manner in which the apparatus achieves the aforescribed desired functions will be readily understood.

The increased water volume handling capacity of the gate 22 is brought about by two means. First, the rear end and side drain channels 29 are of significantly enlarged cross-sectional area, and are of a different cross-sectional shape than is usually employed in under-bunker gates of this type. In the usual gate, the horizontal and

vertical portions 26 and 27 are absent and there exists generally in their place a diagonally upward sloping side wall portion which bridges between the tops of the up-turned edges 24 and the horizontal flanges 28, the inward extending projections of the flanges 28 also being absent. The drainage area thus provided is of generally triangular cross section lying between the diagonally upward sloping portion just mentioned and the outside surface of the lower edge of the bunker chute. The smaller area of the drain channel cross section in the usual case, therefore, restricts the volume of water that can pass into the drain box at any given instant of time and frequently results in the bunker drain water overflowing the sides of the gate.

15 The change in configuration of the gate bottom cross section in the channel region significantly increases the drain channel cross-sectional area and hence permits larger volume discharges from these channels into the drain box thereby reducing and generally eliminating any 20 tendency toward an overflow condition. Additionally, the inclination of the tracks 20 upon which the gate rollers 33 are disposed, causes the entire gate 22 to be inclined toward the drain box 38 so that water draining from the bunker is accelerated toward the drain box 38 and does 25 not tend to pile up in the side and end drainage channels 29. The inclination of the gate 22 in this fashion dictates that the bunker chute front wall 13 be of somewhat greater vertical extent than the bunker chute rear wall 14 in order to maintain substantially the same clearance 30 at all points between the chute bottom and the top surface of the bottom portion of the underlying gate 22 so that any tendency toward washing some of the bunker material into the drain box is minimized.

Observation of FIGURES 3, 4 and 5 reveals the relatively small clearance between the peripherally extending bottom edge of the bunker chute 12 and the underlying outwardly turned horizontal portions 26 of the gate body bottom region. As earlier mentioned, this relatively small clearance causes the bunkered water to flow outward into the channels 29 at a substantial velocity which in the case of the usually constructed gate would result in immediate water spillover and spraying onto the floor below regardless of the water volume handling capabilities of the gate. Such spillover and spraying cannot occur with the illustrated gate construction because it will be appreciated that this high velocity laterally flowing water will be turned up the channel 29 side walls 27 and then turned inwardly against the lower outer surface of the chute bottom by means of the inward projecting portions of the horizontal flanges 28. The high velocity drain water is thus confined to the drainage channels 29 through which it flows along the downwardly sloping channel bottoms 26 toward and into the drain box 38. The tendency toward splashing or spraying of water out of the channel 29 is further reduced by causing the inwardly projecting portions of the horizontal flanges 28 to relatively closely underlie the bottoms of the tracks 20 and the bottom of the chute rear wall reinforcing flange 18 to thereby provide a very narrow opening therebetween through which the spray finds it extremely difficult to pass.

It will, of course, be realized that the particular cross-sectional shape of the closure gate 22, as for example illustrated in FIGURE 3, is not necessarily limited to that illustrated but may be modified for different purposes 65 while still incorporating therein the advantages of the aforescribed invention. By way of illustration, it will be appreciated that a gate designed to close the bottom of a coal bunker need not be formed with the bottom channel structure including the bottom horizontal portion 23 and up-turned side flanges 24 since in the illustrated case the trough so formed is utilized to accommodate the refractory lining material 25 to adequately withstand the heat of the still hot bunkered ash material. Elimination of this channel is readily achieved by merely eliminating the side portions 24 and forming the

gate bottom 23 as a continuous extension of the horizontally outward turned portions 26. Similarly, the cross-sectional area of the drain channel 29 may be materially further increased if desired by extending the outward turned portions 26 to points underlying the side walls 31 and shifting the upward turned portions 27 outward substantially flush with the outer edge of the gate side walls 31. Moreover, the inclination of the tracks 20 along which the gate 22 is shiftable may be more or less than that illustrated in the figures depending upon the particular requirements of the given installation.

Having now described our invention in connection with a particularly illustrated embodiment thereof, it will be understood that modifications and variations will occur from time to time to those persons normally skilled in the art without departing from the essential scope or spirit of the invention, and, accordingly, it is desired to claim the same broadly as well as specifically as indicated by the appended claims.

What is claimed as new and useful is:

1. Under-bunker drained gate apparatus comprising in combination, a chute projecting downward from the bunker, a chute bottom closure gate shiftable between chute opening and chute closing positions, said gate having a bottom portion the top surface of which closely underlies the lower peripheral edge of said chute in spaced relation thereto when said gate is in chute closing position to define a peripherally extending opening therebetween, a drainage channel carried by said gate and communicating adjacent to the bottom thereof with said peripherally extending opening to thereby receive bunker held water passing outward through said opening, a drainage channel discharge means for permitting the escape of drain water out of said drainage channel, and means operatively associated with said drain channel to prevent the drain water from escaping said drain channel except through said discharge means.

2. The apparatus according to claim 1 wherein said drainage channel discharge means comprises a drip ledge at one end of said gate over which the drain water flows out of said drainage channel, and an enclosed drain box secured to said chute, said drain box being apertured to permit penetration of said gate drip ledge thereinto when said gate is in chute closing position.

3. The apparatus according to claim 2 wherein said drain box at the lower edge of the drip ledge aperture is provided with an in-turned flange to prevent drain water from escaping through the aperture by deflecting the same back into the drain box.

4. The apparatus according to claim 1 wherein said drainage channel is inclined to accelerate the flow of drain water toward said discharge means.

5. The apparatus according to claim 1 wherein said drainage channel extends about a substantial portion of the gate bottom periphery and in communication with said opening, the remainder of the gate bottom periphery comprising said drainage channel discharge means.

6. The apparatus according to claim 1 wherein said drainage channel comprises a lateral extension outward beyond the chute side walls of said gate bottom top surface, said surface extension then being turned upward for

a distance and terminating in a surface portion in-turned and projecting toward the outer surface of the chute side walls, whereby high velocity drain water passing outward through said opening is deflected by said surface

5 extensions backward toward the outside surface of said chute and falls back down into said drainage channel, said in-turned surface portion comprising at least a part of said means for preventing escape of drain water from said drainage channel.

10 7. The apparatus according to claim 6 wherein said means for preventing escape of drain water from said drainage channel further includes flange-like elements projecting laterally from the side walls of said chute in closely spaced overlying relationship to the drainage

15 channel in-turned portion which projects toward the outer surface of said chute to thereby prevent water spray from escaping out of the drainage channel through the opening between the chute outer surface and the said in-turned portion projecting theretowards.

20 8. The apparatus according to claim 6 wherein the side walls of said chute carry a pair of parallel disposed tracks inclined at an angle to the horizontal, and wherein said gate carries a plurality of rollers seated upon said tracks for movement therealong and for inclining said gate carried drainage channel at an angle to the horizontal in accordance with the angle of said tracks, the inclination of said tracks being in such sense as to cause accelerated flow of drain water toward said discharge means.

9. The apparatus according to claim 7 wherein the 30 flange-like elements projecting laterally from the side walls of said chute comprise a pair of parallel disposed tracks inclined at an angle to the horizontal, and wherein said gate carries a plurality of rollers seated upon said tracks for movement therealong and for inclining said

35 gate carried drainage channel at an angle to the horizontal in accordance with the angle of said tracks, the inclination of said tracks being in such sense as to cause accelerated flow of drain water toward said discharge means.

40 10. The apparatus according to claim 8 further including gate stop means operative to prevent further shifting motion of said gate along said tracks when said gate is in chute closing position.

11. The apparatus according to claim 8 wherein the 45 lowermost points of said inclined tracks are turned sharply upward to provide roller stop means effective to prevent further shifting motion of said gate along said tracks when said gate is in chute closing position.

12. The apparatus according to claim 8 wherein said 50 drainage channel discharge means comprises a drip ledge at one end of said gate over which the drain water flows out of said drainage channel, and an enclosed drain box secured to said chute, said drain box being apertured to permit penetration of said gate drip ledge thereinto 55 when said gate is in chute closing position.
